DETACHABLE TUFT SECTION BRUSH

William Lawrence Krebs, Plainfield, N. J.

Application February 1, 1947, Serial No. 725,855

2 Claims. (Cl. 306—20)

1

This invention relates to improvements in brushes having detachable tuft sections. It is particularly adaptable for use with paint brushes and brushes for other similar purposes.

A detachable tuft section brush has certain practical and commercially important advantages compared with brushes of the more conventional style having fixed tuft sections. When, for example, the bristles in a fixed section brush become worn or are otherwise unusable, a perfectly good brush handle may necessarily be scrapped along with the brush. With the less expensive brushes the handle represents but a small cost, however, in institutions where large numbers of brushes are consumed daily this rather insignificant cost per brush handle becomes a sizeable matter of expense.

It is the principal object of my invention to provide a brush assembly having a tuft section which is quickly and easily detachable from the brush handle, and, when the handle is assembled with the tuft section, a firm and adequate joinder of parts is effected. A further object of my invention is to provide such a detachable tuft section brush which may be readily manufactured, having a handle which will be useful for a long period of time, and composed of parts which are not deleteriously affected by the action of the usual materials with which brushes are used, or by brush cleaning fluids.

In its preferred embodiment my invention contemplates a brush handle carrying a resilient element which may be quickly and easily inserted within a brush tuft reinforcing section and then deformed to produce internal gripping pressure against the reinforcing section to attach the handle and tuft section. The resilient element is replaceable and the devices employed therewith to give deformation are so arranged as to result in maximum utility and to add strength to the brush handle.

In the drawings,

Figure 1 is a front elevation view showing my invention as it is incorporated in a paint brush, with the tuft section separated from the handle, and

Figure 2 is a view similar to that in Figure 1, showing the tuft section and the handle assembled.

Referring to Figure 1, the handle 10 is shown detached from the tuft section 11. The tubular metal supporting ferrule 12 which reinforces the tuft section is suitably affixed to the brush bristles in any well known manner as by vulcanizing in rubber, insuring a good bond therebetween.

2

Above the line 14, which indicates the extremity of the bristles imbedded in vulcanized material, the ferrule forms an open end socket 12A for the insertion therein of an attaching part of the handle 10. In some instances it may be desirable to include a rippled bead 15 extending circumferentially of the ferrule socket section 12A increasing the rigidity of the socket and also providing an inside and outside surface corrugation. 5 For increased strength there may be added in the trough of the outside corrugation a continuous reinforcing band 16 which may, as shown in the drawings, be a steel wire of circular cross-section or, if preferable, a wire of any other suitable shape 10 such as rectangular. Multiple corrugations may likewise be provided permitting the use of several reinforcing bands depending upon the requirements or, for inexpensive brushes, the bead and the reinforcing bands may be eliminated, the 15 handle of my invention, which is about to be described, being adaptable to ferrule sockets as they are presently produced with the production tools and equipment for nailed handles.

The handle 10 is constructed of wood, although 20 a light weight alloy die casting or other suitable material may be substituted therefor, if desired, and it conforms in shape to the usual paint brush handle. On its upper end, handle 10 is squared off and accommodates a knurled head, elongated 25 fastening screw or rod 21 which is shaped to conform to the handle and extends centrally downwardly through a clearance hole provided in the handle. The lower end of handle 10 is likewise squared off and a flat compression plate 18 is 30 fastened thereto by means of the special shouldered guide pin screws 19. Directly below plate 18 is a resilient deformable member 22 molded of rubber or synthetic rubber and conforming in 35 shape and size with ferrule socket 12A. Clearance holes are cored through member 22 for the pin screws 19 and for the elongated central stud 23 and a slight taper on the sides and radius corners permits unobstructed insertion within the ferrule socket 12A. A second compression plate 18' which confines member 22 upwardly is guided 40 by pin screws 19 and is held in place by the threaded engagement of stud 23 with the downwardly extending fastening screw 21.

Stud 23 is rigidly secured to plate 18' as by soldering or spot welding to prevent its turning with respect to the plate. By extending this stud upwardly beyond the minimum cross-section of handle 10 it is possible to increase the overall physical strength of the handle and also make the 50 threaded engagement with screw 21 remote from

contamination by paints or other material in which the brush is used. A drilled hole 25 is provided in the knurled conical end of screw 21 so that a pin or nail or other implement may be used to tighten or to loosen the threaded connection between stud 23 and screw 21 and a thrust washer 24 is interposed between the head of screw 21 and the top end of handle 10 to absorb wear as the screw is turned. Before joining the handle assembly with the tuft section, the screw 21 is loosely engaged with stud 23 sufficiently to hold the various described parts together but no appreciable tightening is effected such that the member 22 becomes distorted.

Referring now to Figure 2 showing the assembly of parts forming the completed brush, the member 22 has been inserted in the ferrule socket 12A. The cap screw 21 has been tightened and plate 18' is drawn upwardly thereby decreasing the spacing between compression plates 18 and 18' axially of the paint brush handle and thus displacing the material of resilient member 22 laterally. This displacement creates a distributed pressure contact against the inside walls of socket 12A insuring a tight frictional grip between these parts. During distortion material of member 22 also flows to and fills the inside troughs of the corrugations of bead 15 if these are used, enhancing the grip between the respective parts against the tendency for them to be pulled apart. When it is desired to remove the handle from the tuft section the reverse operation is performed by loosening cap screw 21 permitting member 22 to regain its molded shape of Figure 1 whence the parts may be easily separated.

Inasmuch as the ferrule socket substantially completely covers member 22 when the parts are assembled, there is little tendency for any deleterious action on this part by the vehicles of paints or by cleaning fluids, but if it should be necessary, gasketing could be resorted to between the lower end of the handle and the ferrule 12 to create a fluid tight seal. Furthermore, substitutes for rubber or synthetic rubber may be used for member 22 which are not affected by the fluids which it comes in contact with, just so long as the necessary resilience is maintained.

If after continued use the resilient member 22 becomes permanently distorted or worn or otherwise unusable, a new part may be easily substituted. Should a bristle or tuft section become worn or defective or if for any other reason it is desirable to change the tuft section as when changing from one grade or color of paint to another or when changing from work requiring long bristles to that which requires short bristles, then such a change may be quickly and easily made.

It will be understood that various changes may be made in the construction of the parts described, for example, the plate 18 may be dispensed with if the handle 10 should be constructed of metal rather than of wood. Likewise, the stud 23 may extend entirely through the handle

and may have external threads for association with an internally threaded nut on the upper end of the handle. Changes in the shape and size of the component parts and material substitutions 5 may also be made without departing from the invention or from the scope of the appended claims.

What I claim is:

1. A brush of the class described comprising, in combination, a tuft section having a metal reinforcing ferrule, a handle receiving socket of non-circular form formed by the ferrule, a corrugated bead in the metal ferrule extending circumferentially of the handle receiving socket, a reinforcing wire in an outside groove of the corrugated bead, a brush handle corresponding in form at one end with said socket and including a circular form manipulating section at the other end, a resilient non-circular deformable member for insertion in said socket abutting the end of the handle, a compression plate confining the deformable member against the handle, and screw threaded fastening means between the circular end of the handle and the compression plate to exert pressure against the resilient deformable member axially of the brush handle.

2. A brush of the class described comprising, in combination, a tuft section having a handle receiving socket of non-circular form, a brush handle corresponding in form at one end with said socket and including a circular form manipulating section at the other end, a first rigid compression plate affixed to one end of the brush handle, a resilient non-circular deformable member for insertion in said socket abutting the end of the compression plate, a second rigid compression plate spaced from the handle to confine the deformable member against the first compression plate, spaced pins secured to said first plate and engaging said second plate to maintain the said compression plates in alignment, and screw threaded fastening means between the circular end of the handle and the second compression plate to exert pressure against the resilient member axially of the brush handle to create lateral displacement thereof against the inside surfaces of the handle receiving socket.
